United States Patent Office

Des. 205,905
Patented Oct. 4, 1966

205,905

TROWEL

Eugene M. Harrington, 3672 Holboro Drive,
Los Angeles, Calif.

Filed May 3, 1965, Ser. No. 85,074

Term of patent 7 years

(Cl. D51—1)

FIG. 1 is a perspective view showing the new design from one direction; and

FIG. 2 is a perspective view showing the new design from the opposite direction.

The dominant features of my design reside in the portions shown in full lines.

I claim:

The ornamental design for a trowel, as shown and described.
